UNITED STATES PATENT OFFICE.

GEORGE LEWIS GAY, OF SPOKANE, WASHINGTON, ASSIGNOR OF ONE-HALF
TO FRANK EDWIN STARKEY, OF SAME PLACE.

WRAPPING-MACHINE.

SPECIFICATION forming part of Letters Patent No. 634,333, dated October 3, 1899.

Application filed August 26, 1898. Serial No. 689,590. (No model.)

To all whom it may concern

Be it known that I, GEORGE LEWIS GAY, of Spokane, in the county of Spokane and State of Washington, have invented a new and Improved Wrapping-Machine, of which the following is a full, clear, and exact description.

The object of the invention is to provide a new and improved wrapping-machine for newspapers, pamphlets, circulars, or the like which is simple and durable in construction and arranged to deliver the material for forming the wrappers from an endless roll and then securely and firmly place the wrapper around the newspaper, circular, or other paper to be wrapped and at the same time fold both the wrapper and paper and finally cut the wrapper from the endless roll and seal the end of the wrapper and deliver the paper completely wrapped ready for mailing.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a rear elevation of the improvement. Fig. 2 is a side elevation of the same with the support for the slide-head removed. Fig. 3 is an enlarged sectional plan view of the improvement on the line 3 3 in Fig. 2. Fig. 4 is a sectional side elevation of the same with parts in a different position. Fig. 5 is a transverse section of the pasting device on the line 5 5 in Fig. 4. Fig. 6 is a sectional side elevation of the improvement with parts in a different position, the section being on the line 6 6 in Fig. 7; and Fig. 7 is an end elevation of the improvement, looking in the direction of the arrows, on the line 7 7 in Fig. 6.

The improved wrapping-machine is mounted on a suitably-constructed frame A, supporting at its upper end a table B, over which pass the partly-folded newspapers C, circulars, or the like to be wrapped in wrappers C', formed from a roll of wrapping material C², mounted to turn in bearings held on brackets B', depending from the table B, as is plainly indicated in Figs. 1 and 2. The wrapping material C' passes over the peripheral sur-

face of a feed-cylinder D, secured on a shaft E, extending transversely and journaled in suitable bearings on the frame A. On one outer end of the shaft E is secured a gear-wheel E', pressed on by a spring E², the said gear-wheel E' being in mesh with a mutilated gear-wheel F', secured on the main shaft F, journaled in suitable bearings on the frame A, and provided with a pulley F², connected by belt with other machinery, so as to impart a rotary motion to the shaft, which by the mutilated gear-wheel F' imparts an intermittent rotary motion to the gear-wheel E' and the feed-cylinder D. The gear-wheel E' is also in mesh with a second gear-wheel G' of the same size as the gear-wheel E' and secured on a shaft G, journaled in suitable bearings on the top of the frame A. The spring E² serves to hold the wheel E' in proper place when the driving-wheel stops. The wheel E' when pressed on by the spring is not liable to be carried past a proper position by its own momentum.

On the shaft G are secured arms H', connected by springs H² with a segmental pad H, operating in conjunction with the feed-cylinder D to feed the newspaper C and the wrapping material C', as hereinafter more fully described. On the segmental pad H are held spaced spring guide-arms H⁴ for guiding the paper and wrapper, as herein-after more fully described, the arms having their rear ends firmly attached to the peripheral surface of the pad, the forward ends extending normally a distance from the pad, as shown in Fig. 6. The arms are pressed onto the pad while coming in contact with the cylinder D; but the arms by their own resiliency return to their original position as soon as they leave the cylinder D, as shown in Fig. 6, and serve to guide the paper and wrapper to the wrapping device. A guide-plate D², similar to the guide-arms H⁴, and likewise serving to guide the paper C and wrapping material C', extends across the cylinder D and is formed with fingers and is secured at its ends on gravity-arms D', hung or pivoted on the ends or heads of the cylinder D. Stop-pins D³ on the cylinder-heads serve to limit the swinging motion of the gravity-arms D' to hold the guide-plate D².

free of the rim of the cylinder opposite the guide-arms H^4 , as plainly shown in Fig. 6, the said guide-plate lying flat on the rim while passing the pad H . One of the arms H' also supports a perforating-knife I , preferably having a serrated edge, as plainly shown in Figs. 1, 3, and 4, to cut the wrapping material C' at the proper time to form a complete wrapper for a corresponding news-
paper, pamphlet, or the like. The serrations of the knife I operate in conjunction with a narrow slot D^4 , formed transversely in the rim of the cylinder adjacent to a pasting-opening D^5 , formed in the cylinder, and at which opening the paste is applied to the wrapping material, the latter being cut in the rear of the applied paste by the knife I , operating in conjunction with the slot D^4 . (See Fig. 4.) The paper C and the wrapping material C' pass from the cylinder D , its guide-plate D^2 , the segmental pad H , and its guide-arms H^4 to a wrapping device formed with a casing J , made in two parts $J' J^2$, secured on arms $J^3 J^4$, hung loosely on the shafts E and G , respectively, the arms being connected with each other by springs J^5 , so as to permit the casing members or sections $J' J^2$ to open and close, as hereinafter more fully described.
The casing members J' and J^2 are provided at their inner faces with spaced ribs J^6 and J^7 , extending beyond the upper edges to form fingers between which pass the free ends of the guide-arms H^4 and the fingers of the plate D^2 , respectively, to insure a safe delivery of the paper and wrapping material from the pad H and the cylinder D to the casing J . The spaced ribs J^6 and J^7 serve to prevent endwise movement of the paper and wrapper while the wrapping-plates K are drawn outward, as hereinafter more fully described.
Into the casing J extend from opposite sides pairs of wrapping-plates K , the plates of each pair being secured at their outer ends on a spindle K' , mounted to turn in a head L , fitted to slide on guideways N , supported from the main frame A . (See Fig. 1.) The heads L are normally held in an innermost position by the action of contractile springs N' , coiled on the guideways N and secured at one end to the corresponding head and at the other end to the corresponding guideway. The heads L are pivotally connected by links O with levers O' , fulcrumed at O^2 at the lower portion of the frame A , and the levers are connected by links O^3 with an upwardly-extending arm O^4 , adapted to be engaged by a cam O^5 , secured on the shaft F . When the latter is rotated, then the cam O^5 imparts a downward-sliding motion to the arm O^4 , which is guided in a suitable bearing A' on the frame A , so that the links O^3 impart an outward-swinging motion to the levers O' to move the heads L simultaneously outward on the guideways N against the tension of the springs N' . When this takes place, the wrapping-plates K move outward out of engagement with the

wrapped newspaper to allow the latter to pass by its own gravity out of the casing J , and when this has taken place the cam O^5 moves into such position as to allow the arm O^4 and the parts connected therewith to return to their normal position by the action of the springs N' —that is, the plates pass back into an innermost position within the casing J . 75

Each pair of plates K is provided with bevels K^2 , adapted to engage rollers P' , extending in an opening P^2 , formed in a gear-wheel P , in which the said rollers are journaled, said gear-wheel being mounted to turn 80 on guide-rollers Q , journaled on the frame A , the gear-wheels being in mesh with mutilated gear-wheels F^3 , of which one is secured on the shaft F and the other is integral with the gear-wheel F' , also secured on the said shaft F . 85 Thus when the latter is rotated an intermittent rotary motion is given to the gear-wheels P , which by their friction-rollers P' impart a rotary motion to the wrapping-plates K at the time the latter are in an innermost position, 90 so that the newspaper and the wrapping material are wrapped together, the inner surface of the casing-sections $J' J^2$ pressing against the wrapping material and the newspaper as the casing-sections open and close by the turning action of the wrapping-plates. A regulating and retaining spring P^1 is employed (see Fig. 3) for engaging the outer face of each gear-wheel P to place and hold the latter in position when left by the mutilated gear-wheel F^2 . 95

It is understood that the springs J^5 insure a closing of the casing-sections when the plates stand approximately parallel with the sides of the casing-sections, as indicated in Fig. 4; 105 but when the plates move into an inclined position relative to the sides of the casing-sections then the latter are pushed apart for the purpose above mentioned—that is, to bear against the wrapping material and the newspaper to press the same in firm contact while winding the same on the wrapping-plates. 110

The plates of each pair of wrapping-plates K are adapted to move toward each other at their inner ends when moving into an innermost position—that is, when the heads L are turned inward by the action of the springs N' and the inclines K^2 of the plates K come in contact with the rollers P' . At this time the newspaper and the wrapping material have 120 passed into the casing and are thereby clamped between a pair of wrapping-plates, so that when a rotary action is given to the wrapping-plates from the gear-wheels P , as previously mentioned, then the newspaper 125 and the wrapping material can be wrapped up by the wrapping-plates.

When the heads L are moved outward by the action of the cam O^5 , as previously explained, then the inner ends of the wrapping-plates K move out of the wrapped newspaper, and the latter is free to drop out of the casing J . 130

The casing-sections $J' J^2$ are preferably cor-

rugated, as is plainly indicated in Fig. 3, so as to properly press against the wrapper and paper to insure a proper folding of the two. It is understood that the wrapping-plates make 5 a sufficient number of revolutions for each newspaper and its wrapper to properly fold and wrap the same and to bring the end of the wrapper back upon the body portion of the wrapper to seal the wrapper, as this end 10 is supplied with an adhesive substance, such as paste, delivered from a pasting device contained within the cylinder D.

The device is arranged as follows: Within 15 the cylinder D is suspended a pot R, containing paste or other suitable adhesive substance, and in the upper and lower ends of said pot are journaled rollers R' R², over which passes an endless band R³, the lower portion of which extends in the paste contained in 20 the pot. On the uppermost roller R' is secured a star-wheel R⁴, adapted to be engaged at every revolution of the cylinder D by a pin D⁶, projecting from one of the heads of the cylinder, so as to impart an intermittent 25 rotary motion to the star-wheel and roller to cause the band R³ to travel through the adhesive substance contained in the pot R. The upper end of the band R³ is close to the inner surface of the rim of the cylinder D, 30 and the said top part of the band is adapted to pass into and up the opening D⁵, formed in the rim of said cylinder, to bring the adhesive substance to the under side of the wrapping material C' at the time the said 35 opening D⁵ is at the top. The star-wheel R⁴ revolves in an opposite direction to the cylinder D, and consequently motion is given to the band R³ in an opposite direction to the wrapping material C' to insure a thorough 40 and economical application of the paste. Now in order to lift the pot within the cylinder I provide the heads of the cylinder D with cams D⁷, adapted to engage lugs R⁵, projecting from the sides of the pot R, (see 45 Figs. 4 and 5,) so that when the cylinder revolves the cams D⁷ engage the lugs R⁵, so as to lift the pot R at the time the roller R' is at the beginning of the opening D⁵. The shaft E, carrying the feed-cylinder D, is made 50 in sections and on the adjacent ends is hung the paste-pot R, the sides of which have elongated bearings R⁶ for the ends of the shaft to allow the pot to move upward when the cams D⁷ come in contact with the lugs R⁵, 55 as will be readily understood by reference to said Figs. 4 and 5.

The cylinder D, with its opening D⁵, moves into an uppermost position at about the time the wrapping material C' has been fed forward 60 to nearly the size of the wrapper, so that it is the end portion of the wrapper that receives the adhesive substance from the band or belt R³, it being understood that the wrapper is cut off from the roll of material by the 65 knife I, operating in conjunction with the slot D⁴ of the cylinder D. When the roller R' is near the end of the opening D⁵, then the cam

D⁷ disengages the lugs R⁵, and consequently the pot R' drops back to its former position to bring the roller within the surface of the 70 cylinder, the pot being normally supported by the shaft E, without, however, rotating with the same. The lower end or bottom of the pot is preferably weighted to hold the pot always in a vertical position. 75

After the wrapped paper leaves the casing J it drops into a receptacle S, preferably made cylindrical and journaled in suitable bearings in the frame A, wings S' being arranged radially in the said receptacle for receiving 80 the paper between adjacent wings. Each of the wings is provided with a lug S², adapted to be engaged by the cam O⁵ at every revolution of the shaft F, so as to turn said receptacle and dump the paper out of the same 85 into a suitable receptacle held below.

The operation is as follows: The end of the wrapping material C' is placed over and between the feeding-cylinder D and pad H, tension being applied to the roll of wrapping 90 material to prevent it from unwinding faster than it is used and to regulate the degree of firmness of a wrapped paper. A paper partially folded as it comes from the printing-press is now placed upon the slanting shelf 95 B, the lower edge of the paper resting against and between the cylinder D and the forward end of the pad H, these two parts being in the position shown in Fig. 4 of the drawings and motionless, as are also the wrapping-plates 100 K K, which have been drawn outward. The revolving gear-wheel F' now picks up the gear of the gear-wheel E', causing the same, together with the gear-wheel G', to revolve sufficiently to carry forward the cylinder D and 105 pad H, between which the paper C and the end of the wrapping material C' are fed in between the casings J' J². The pad H now having passed the point of bearing on the cylinder D, the paper C is left free to drop 110 by its own weight to a point where the wrapping-plates K K, relieved of the action of the cam O⁵, allow the springs N' to draw said wrapping-plates K K inwardly, clamping the paper about midway of its upper and lower 115 ends, the receptacle S retaining the paper, the lower edge of the latter resting upon the same until clamped by the wrapping-plates K K. The end of the material C' ceases advancing 120 when the pad H has passed the point of bearing on the cylinder D, being advanced only far enough to be taken between the wrapping-plates K K. The wrapping material is thus left free to be unwound from the roll C² by the action of the wrapping-plates K K in wrapping 125 it about the paper C. At this point the gear-wheels P P are picked up by the gear-wheels F², giving the wrapping-plates K K the necessary number of revolutions to wrap up the paper and wind the wrapper about it. 130 While the wrapping material is being drawn over the revolving cylinder D by the action of the wrapping-plates K K in wrapping the same in and about the paper C, the material

C' is pasted by coming in contact with the pasting-band R³, projecting through the opening D⁵ in the cylinder D and which extends across the face of the cylinder. The cylinder is geared to bring the opening D⁵ in the same at the top, and the wrapping material C' is pasted immediately in front of where the wrapper will be cut off. The wrapping material C' continues traveling with the revolving cylinder D until met by the points of the perforating-knife I, which perforates the wrapping material C' across its width immediately in the rear of the pasted portion. The cylinder D and arms II', carrying the pad H and perforating-knife I, momentarily stop revolving, allowing the continued revolving of the wrapping-plates to sever the wrapper from the wrapping material C' at the place perforated. The wrapping-plates K K continue to revolve, winding the remaining and pasted portion of the wrapper and then stop revolving. The cam O⁵ now coming into action withdraws the wrapping-plates K K outward from the completely-wrapped paper.

- 25 The wrapping-plates now being free spring apart the casings J' J² from each other, allowing the wrapped paper to drop by its own weight into the receptacle S. The cam O⁵ in its continued revolution causes the receptacle S to revolve and dump the completely-wrapped paper.
- 30 From the foregoing it will be seen that the machine is very simple and durable in construction, is not liable to get out of order, and properly wraps a newspaper and folds the same and seals the wrapper automatically, so that the newspaper is discharged from the machine completely wrapped ready for mailing.
- 40 Having thus fully described my invention, I claim as new and desire to secure by Letters Patent—

1. A wrapping-machine comprising a feeding device, and a wrapping device consisting of a sectional casing formed of spring-pressed members, and into which passes the paper and the wrapper from said feeding device, the paper and wrapper entering the casing at its upper end, and spring-pressed wrapping-plates mounted to turn and to slide in said casing, substantially as described.

2. A wrapping-machine, comprising a feeding-cylinder, a segmental pad rotating in unison therewith for feeding the paper and wrapper simultaneously, and a wrapping device into which passes the paper and the wrapper, said wrapping device consisting of a sectional casing formed of spring-pressed members, and spring-pressed plates mounted to turn and to slide in said casing, substantially as shown and described.

3. A wrapping-machine, provided with a feeding device comprising a feeding-cylinder, a segmental pad, and arms mounted to turn and connected by springs with the said pad, the feeding-cylinder and pad rotating in unison, substantially as shown and described.

4. A wrapping-machine, provided with a feeding device comprising a feeding-cylinder, a segmental pad, arms mounted to turn and connected by springs with the said pad, the cylinder and pad rotating in unison, guide-arms carried by the said pad, and a guide-plate extending across the cylinder and formed with fingers, substantially as shown and described.

5. A wrapping-machine, provided with a feeding device comprising a gumming or pasting cylinder having a pasting-opening and a transverse slot adjacent to the pasting-opening, a segmental pad, arms mounted to turn and connected with the said pad the said pad rotating in unison with the said cylinder and a knife-blade supported by one of said arms and operating in conjunction with said transverse slot, substantially as shown and described.

6. A wrapping-machine provided with a wrapping device comprising a sectional casing into which the paper and the wrapper are delivered, the said casing having spring-pressed members, and arranged to receive the paper and wrapper between the members of the casing at the upper end thereof and to discharge the wrapped paper at the lower end, wrapping-plates for clamping the paper and the wrapper within the casing, springs normally holding the said wrapping-plates in an innermost position, means for moving the wrapping-plates outward against the tension of the springs, and means for intermittently turning the said plates and wrapping the paper and wrapper and pressing the same against the yielding casing members, substantially as shown and described.

7. A wrapping-machine provided with a wrapping device comprising a sectional casing having spring-pressed members, wrapping-plates for clamping the paper and the wrapper within the casing, a spindle at the outer ends of the plates of each pair, heads in which the said spindles are mounted to turn, guideways on which the said heads are mounted to slide, springs coiled on the guideways and normally holding the heads in an innermost position and means for intermittently turning the said plates and wrapping the paper and wrapper and pressing the same against the yielding casing members, substantially as shown and described.

8. A wrapping-machine, provided with a wrapping device, comprising a sectional casing having spring-pressed members, wrapping-plates for clamping the paper and wrapper within the casing, a spindle on which the outer ends of the plates of each pair are secured, heads in which the said spindles are mounted to turn, the said heads being fitted to slide on guideways, springs normally holding the said heads in an innermost position, means for intermittently turning the said plates and wrapping the paper and wrapper and pressing the same against the yielding casing members, and means for moving the

heads outward on the guideways against the tension of the springs to carry the wrapping-plates out of the wrapped paper, substantially as shown and described.

5 9. A wrapping-machine, provided with a pair of wrapping-plates mounted to turn and adapted to clamp the paper and wrapper and wind the latter around the plates, and a casing containing the said plates and comprising 10 two members, spring-connected arms carrying the said members, and loosely supported, the said members of the casing being corrugated and adapted to be engaged and pressed upon by the said wrapping-plates to 15 cause the members to press the paper and its wrapper, substantially as shown and described.

10 10. A wrapping-machine, provided with a pair of wrapping-plates mounted to turn and 20 adapted to clamp the paper and wrapper and wind the latter around the plates, yieldingly-mounted casing members containing the said plates and adapted to be engaged and pressed open by the said plates to cause the members to 25 press the paper and its wrapper, a gear-wheel mounted to turn, rollers journaled in the said gear-wheel and adapted to be engaged by inclines on the said wrapping-plates, and means for imparting an intermittent rotary motion 30 to the gear-wheel, substantially as shown and described.

11. A wrapping-machine provided with a wrapping device comprising yieldingly-mounted casing members, a pair of spring-35 pressed wrapping-plates connected at their outer ends, and mounted to turn and to slide in said casing, the said plates being provided with inclines, and rollers adapted to be engaged by the inclines when the wrapping-40 plates are moved inward to cause the inner ends of the plates to move toward each other to clamp the paper and wrapper, substantially as shown and described.

45 12. A wrapping-machine, provided with a feeding device comprising a gumming or pasting cylinder, and a spring-supported segmental pad rotating in unison with the said cylinder, the said pad being provided with spaced spring guide-arms for guiding the paper and wrapper, the forward ends of the 50 said guide-arms extending normally from the pad, substantially as shown and described.

13. A wrapping-machine, provided with a feeding device, comprising a gumming or pasting cylinder, a shaft on which said cylinder is secured, a shaft rotating in unison with the shaft of the pasting-cylinder, arms secured to the said shaft, and a segmental pad connected by springs with the said arms, the said pad 55 being provided with guide-arms and operating in unison with the said cylinder, substantially as shown and described.

60 14. A wrapping-machine, provided with a feeding-cylinder, a segmental pad having 65 guide-arms and rotating in unison with the said cylinder, a guide-plate extending across the cylinder and secured at its ends on gravity-

arms held on the end of the cylinder, and means for limiting the swinging motion of the gravity-arms, substantially as shown and de- 70 scribed.

15. A wrapping-machine, provided with a feeding device comprising a gumming or pasting cylinder, a segmental pad having guide-arms rotating in unison with the said cylinder, and a knife carried by the said pad, and adapted to engage and cut the wrapping material, substantially as shown and described. 75

16. A wrapping-machine, provided with a feeding device, comprising a cylinder having 80 an opening in its periphery, a gumming or pasting device carried within the said cylinder and adapted to deliver the paste to the wrapping material at the said opening, a segmental pad having guide-arms and rotating 85 in unison with the said cylinder, and a knife carried by the said pad, and adapted to engage and cut the wrapping material, substantially as shown and described.

17. A wrapping-machine provided with a 90 feeding-cylinder having an opening in its periphery, a gumming or pasting device carried within the said cylinder, and comprising a receptacle for the pasting or gumming material suspended within the cylinder, means for 95 raising said receptacle and means carried by the receptacle for delivering the material through the opening to the wrapping material when the receptacle is raised, substantially as shown and described. 100

18. A wrapping-machine, provided with a feeding-cylinder having an opening in its periphery, a gumming or pasting device carried within the said cylinder, and adapted to deliver the paste to the wrapping material at 105 the said casing-opening, the said device comprising a paste-pot suspended within the cylinder, rollers journaled in the upper and lower ends of said pot, an endless band passing over the said rollers and through the binding substance in the pot, and adapted to deliver the paste through the opening to the wrapping material, a star-wheel secured to one of said rollers and a pin projecting from one of the cylinder-heads and adapted to 115 engage the star-wheel at each revolution of the cylinder, substantially as shown and described. 110

19. A wrapping-machine, provided with a 120 feeding-cylinder having an opening in its periphery, a gumming or pasting device carried within the said cylinder, and adapted to deliver the paste to the wrapping material at the said casing-opening, the said device comprising a paste-pot suspended within the cylinder, an endless band passing through the binding substance in the pot, and adapted to deliver the paste through the opening to the wrapping material, means for imparting an 125 intermittent traveling motion to the said band from the revolving cylinder, and means for raising the said pot and band within the cylinder, to project the band through the opening, substantially as shown and described. 130

20. A wrapping-machine, provided with a feeding-cylinder having an opening in its periphery, a gumming or pasting device carried within the said cylinder, and adapted to deliver the paste to the wrapping material at the said casing-opening, the said device comprising a paste-pot suspended within the cylinder, an endless band passing through the binding substance in the pot, and adapted to deliver the paste through the opening to the wrapping material, and means for raising the said pot and band within the cylinder, to project the band through the opening, substantially as shown and described.
- 15 21. A wrapping-machine, provided with a feeding-cylinder having an opening in its periphery, a gumming or pasting device carried within the said cylinder and adapted to deliver the paste to the wrapping material at the said opening, the said device comprising a paste-pot suspended within the cylinder, an endless band passing through the binding substance in the pot, cams on the heads of the cylinder, and lugs projecting from the sides of the pot and adapted to be engaged by the said cams when the cylinder revolves to lift the pot to project the band through the opening in the cylinder, substantially as shown and described.
- 20 22. A wrapping-machine, comprising a feeding-cylinder, a segmental pad rotating in unison therewith for feeding the paper and wrapper simultaneously, guides carried by the pad and cylinder to guide the paper and wrapper, and a wrapping device into which passes the paper and the wrapper, said wrapping device consisting of a sectional casing formed of spring-pressed members, each member being provided at its inner face with spaced ribs extending beyond the upper edges and forming fingers between which pass the ends of the guides carried by the cylinder and pad, and spring-pressed wrapping-plates mounted to turn and to slide in said casing, substantially as shown and described.
- 25 23. A wrapping-machine, comprising a feeding-cylinder, a shaft on which said cylinder is secured, a gear-wheel on said shaft and adapted to be engaged by a mutilated gear-wheel secured to the main shaft, a segmental pad having guide-arms, a shaft carrying said pad

and provided with a gear-wheel in mesh with the gear-wheel on the cylinder-shaft, a gumming or pasting device carried by the said cylinder, a knife adapted to engage and cut the wrapping material, and a wrapping device into which passes the paper and the wrapper, substantially as shown and described.

24. In a wrapping-machine, a wrapping device provided with wrapping-plates for clamping the paper and wrapper, the said plates being mounted to turn and to slide, means for turning the said plates and wrapping the paper and wrapper, a receptacle into which the wrapped paper passes from the wrapping device and means for turning the said receptacle to discharge the wrapped paper therefrom, the said means also controlling the sliding movement of the wrapping-plates to withdraw the same from the wrapped paper, substantially as described.

25. A wrapping-machine provided with a wrapping device comprising a casing formed of spring-pressed members, and wrapping-plates for wrapping the paper and wrapper the said wrapping-plates being mounted to turn and to slide in the said casing, a cam mounted to revolve, means actuated by the cam for moving the wrapping-plates out of the wrapped paper, and a receptacle into which passes the wrapped paper from the wrapping device, the said receptacle being revolved by the said cam, substantially as described.

26. In a wrapping-machine, a sectional casing comprising yieldingly-mounted members provided on their inner faces with spaced ribs, and wrapping-plates mounted to turn and to slide in said casing, substantially as described.

27. A wrapping-machine comprising a feeding device, and a wrapping device consisting of a casing formed of two yieldingly-mounted members, arranged to receive between them the paper and wrapper from the feeding device, the upper edges of said casing members being provided with guides, and wrapping-plates mounted to turn and to slide in said casing, substantially as described.

GEORGE LEWIS GAY.
